Primary Examiner — Philip S Hyder*Assistant Examiner* — Sydney Buffalow(74) *Attorney, Agent, or Firm* — Themis Law(57) **CLAIM**

The ornamental design for an adjustable platform, as shown and described.

DESCRIPTION

FIG. 1 is a front-right side perspective view of an adjustable platform showing my new design;

FIG. 2 is a rear-right side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The portions of the figures in broken lines form no part of the claimed design.
